US00D834590S

(12) **United States Design Patent** (10) Patent No.: **US D834,590 S**
Engelhard et al. (45) Date of Patent: **** Nov. 27, 2018**

- (54) **DISPLAY SCREEN OR PORTION THEREOF WITH GRAPHICAL USER INTERFACE**

(71) Applicant: **Gecko Health Innovations, Inc.**,
Cambridge, MA (US)

(72) Inventors: **Yechiel Engelhard**, Boston, MA (US);
Mark Maalouf, Cambridge, MA (US)

(73) Assignee: **Gecko Health Innovations, Inc.**,
Cambridge, MA (US)

(**) Term: **15 Years**

(21) Appl. No.: **29/600,384**

(22) Filed: **Apr. 12, 2017**

CLAIM

The ornamental design for a display screen or portion thereof with graphical user interface, as shown and described.

DESCRIPTION

FIG. 1 is a front view of a display screen or portion thereof with graphical user interface showing our new design; FIG. 2 is a front view of a second embodiment thereof; and, FIG. 3 is a front view of a third embodiment thereof.

The broken line showing of the text, the remainder of the graphical user interface, and display screen and the remainder of the device containing the display screen with graphical user interface in the figures are for environmental purposes only and form no part of the claimed design.

1 Claim, 3 Drawing Sheets
